UNITED STATES PATENT OFFICE.

AUGUST J. HARTFIELD, OF LOS ANGELES, CALIFORNIA.

FUMELESS STACKLESS HEATER.

1,371,481.

Specification of Letters Patent. Patented Mar. 15, 1921.

Application filed April 23, 1918. Serial No. 230,359.

To all whom it may concern:

Be it known that I, AUGUST J. HARTFIELD, a citizen of the United States, residing at Los Angeles, in the county of Los Angeles, State of California, have invented new and useful Improvements in Fumeless Stackless Heaters, of which the following is a specification.

This invention relates to that class of heaters generally known as gas heaters and generally used for domestic and similar heating purposes; and it is the object of this invention to provide in simple and inexpensive form an efficient heater which will efficiently deliver heat to the surrounding atmosphere and deliver no objectionable fumes into the atmosphere; although unprovided with a draft stack. It is also a particular object to provide such a heater in simple and inexpensive form, capable of being easily manufactured and assembled.

With these and other objects in view my invention will be best understood from the following description of a preferred specific form of device embodying the invention, reference being had for this purpose to the accompanying drawings in which—

Figure 1 is a vertical central longitudinal section of my improved heater; Fig. 2 is an enlarged horizontal section taken on line 2—2 of Fig. 1; and Fig. 3 is a vertical transverse section taken on line 3—3 of Fig. 1.

In the drawings I show a heater which is made up in the form of a radiator and, in the specific and preferred form herein shown and described, I utilize a central combustion chamber in which the burner is located and on each side of this central combustion chamber I have a plurality of radiating elements 10 through which the heated gases flow and from which heat is radiated. These radiator elements 10 may be designed in any suitable form and each contain a vertical passage 11 with openings at top and bottom as shown at 12, the outermost elements 10 having openings on one side only. These elements are all held together and held to the central combustion chamber by means of bolts 13 and 14, and tight joints are made between the adjacent elements by means of tapered nipples 15 which fit into the tapered openings 12; the bolts 13 and 14 holding the parts tightly together.

The combustion chamber is made up with side walls 20 preferably of cast iron, and

with front and back walls 21 of sheet metal in a single piece which has an opening in its central portion passing over the top and forming the top of the element, as indicated at 22 in Fig. 3. The sheet metal 21 is held between the two side walls 20 by having its edges fit into grooves as shown at 24 in Fig. 2, the parts being held together by the bolts 13 and 14. The side walls 20 have openings 12^a above and below, through which communication is established with the radiator elements 11, connection being made through the nipples 15 forming tight joints.

Within the combustion chamber casing thus formed, I place a ring-shaped burner 25 which is supplied with gas through pipe 26 which leads downwardly from the burner and then forwardly to the forward side of the heater. In front of the burner, in the front wall 21, there may be a door 21^a, which may be opened for igniting the gas at the burner. The burner has its burner openings 27 placed so that the flame from the burner will be thrown inwardly directly onto a set of vertical tubes 28 through which the heated air and gases of combustion pass upwardly, as will be hereinafter described. These tubes 28 may be made of any suitable material; they may be made of fire resisting material, such as fire clay; or they may be made of cast iron. I preferably make these tubes integral with a lower flange 29 and an upper head 30. The lower flange 29 rests upon a shoulder 31 around an opening 32 in the upper part of a cross tube 33 which crosses beneath the combustion chamber immediately below the burner. This cross tube 33 is of annular shape in cross section at each end, as will be noted by an inspection of the several views, but at substantially its central portion is enlarged to an oval shape and is provided at its top with the circular opening 32. This cross-tube 33 has its annular ends set in grooves at 34 as shown in Fig. 1, and is held in place by the end walls 20 of the chamber being held upon it by the bolt 14. The tubes 28 are thus in communication with this cross tube 33 which communicates with the openings 12^a through which communication is established with the radiator elements 11. The upper ends of tubes 28 communicate with the lower part of a casing 35. This casing 35 rests upon the upper head 30 of tubes 28 and its upper end extends to the upper end of the combustion

chamber, where it extends into the opening in the sheet metal side piece 21, and is there provided with a perforated cover 36. In this casing 35 a removable can 37 is placed, having a perforated bottom as shown at 38, and having preferably a handle at its top at 39 so as to be removable from the casing 35. This can is filled with bodies 40, preferably spherical, formed of a material which 10 will absorb or neutralize the sulfurous and other objectionable fumes in the gases of combustion. The can is easily removable to renew the substance which absorbs or neutralizes the fumes. Various substances may 15 be used for this purpose, for instance an alkaline substance pressed into the required form.

When the device is in operation, air is 20 drawn in through the open lower end of the combustion chamber up to the burner 25, supplying the burner with a sufficient amount of air for good combustion. The flame is projected directly inwardly against tubes 28, heating those tubes to a high temperature. The products of combustion, and 25 the heated air along with it, pass upwardly through the combustion chamber around the casing 35, heating that casing and heating its contents, and then the products of combustion pass out through the openings at 30 the upper end of the combustion chamber into the radiator elements. Here the hot gases pass down the radiator elements, and the heat of the gases is conducted and radiated through the walls of the radiator elements into the surrounding atmosphere. The gases are thus cooled and the cooling 35 gases pass downwardly through the radiator elements and thence through the openings at their bottom back into the cross tube 33. Here the gases and air pass upwardly 40 through the tubes 38 into the casing 35 and can 37. They are here again heated to a high temperature, both during their passage 45 through the tubes 38 and during their passage through the can 37. The gases, purified by their passage through the material 40, together with the heated air drawn through the burner, are thus delivered 50 through the cover 36 into the surrounding atmosphere. Being fumeless, these gases are not objectionable; and they carry into 55 the atmosphere of a room a very great amount of heat which would otherwise be lost if the gases were carried off in a stack. It will be noted that the heated gases and air travel in a relatively long and circuitous route through the heater, thereby dropping and radiating all of their heat. It 60 will further be noted that the subsequent heating of the gases, just prior to their final discharge into the atmosphere, not only conduces to efficient delivery of heat to the atmosphere, but also assists in causing the

proper and rapid circulation of air through 65 the heater.

While I have proceeded to describe my invention in some detail and particularity, it will be understood that I do not thereby limit my invention to such details as herein 70 described, reserving to myself such changes and modifications as may occur to those skilled in the art, or as may fall within the scope of the following claims.

Having described a preferred form of my 75 invention, I claim:

1. In a radiator of the character described, a vertical combustion chamber, a side radiator element in communication with the upper part of the chamber, a cross tube beneath the chamber in communication with the lower part of the side radiator element, a plurality of vertical tubes communicating with and rising from said cross tube, a casing communicating with said tubes and extending upwardly therefrom within the combustion chamber and discharging into atmosphere at its upper end, and a burner in the combustion chamber around the said vertical tubes and adapted to heat said tubes. 90

2. In a radiator of the character described, a vertical combustion chamber, a side radiator element in communication with the upper part of the chamber, a cross tube beneath the chamber in communication with the lower part of the side radiator element, a plurality of vertical tubes communicating with and rising from said cross tube, a casing communicating with said tubes and extending upwardly therefrom within the combustion chamber and discharging into atmosphere at its upper end, a receptacle in the casing containing fume absorbing material, and a burner in the combustion chamber around the said vertical tubes and adapted 105 to heat said tubes.

3. A radiator of the character described, comprising a vertical combustion chamber and a plurality of side radiating elements, the combustion chamber and the side radiating elements having side apertures at top and bottom, means to hold the chamber and elements together with their apertures in register, and means to form a tight joint at the registering apertures; a cross tube beneath 110 the combustion chamber and communicating with the lower apertures of that element, an annular gas burner above said cross tube, a plurality of heating tubes extending vertically from the upper part of the cross tube 115 and communicating therewith at their lower ends, said heating tubes being located within said burner, and said burner being provided with burner openings to project its flame inwardly against said tubes to heat 120 them and to heat the gases and air passing through said tubes, a central cylindrical casing communicating at its lower end with the 125

upper end of said heating tubes, and extending upwardly to the upper end of the combustion chamber, a removable cover for the upper end of said casing, and a removable can in said casing having a perforated bottom and adapted to contain a fume absorbing material.

4. In a radiator of the character described, a vertical combustion chamber, side radiator elements in communication with the upper part of the chamber, a casing extending vertically through the combustion chamber from near its lower end to its upper end and open at the upper end into the atmosphere, said casing being substantially central of the combustion chamber and there being an annular space around the casing within the combustion chamber, means by which the side radiator elements communicate with the lower end of the casing, and an annular burner in the combustion chamber.

5. In a radiator of the character described, a vertical combustion chamber, side radiator elements in communication with the upper part of the chamber, a casing closed off from and extending vertically through the combustion chamber and open at its upper end, means by which the side radiator elements communicate with the lower end of the casing, a burner in the combustion chamber adapted to heat the casing and the gases of combustion passing therethrough, and a fume absorbing material in said casing and through which the heated gases of combustion must pass before discharging.

6. In a radiator of the character described, an elongated combustion chamber, a radiator element in communication with one end of the combustion chamber, a casing extending

through the combustion chamber from one end to a point adjacent its other end and open at one end into the atmosphere, said interior casing being substantially central of the combustion chamber and there being a space around the same within the combustion chamber, means by which the radiator element communicates with the interior of the casing, and a burner in the combustion chamber, the gases of combustion passing through the radiator element and making their exit through the central casing in the combustion chamber.

7. In a radiator of the character described, an elongated combustion chamber, a radiator element in communication with one end of the combustion chamber, a casing extending through the combustion chamber from one end to a point adjacent its other end and open at one end into the atmosphere, said interior casing being substantially central of the combustion chamber and there being a space around the same within the combustion chamber, means by which the radiator element communicates with the interior of the casing, a burner in the combustion chamber, and a fume absorbing material in said casing through which the heated gases of combustion must pass before discharging, the gases of combustion passing through the radiator element and making their exit through the central casing in the combustion chamber.

In witness that I claim the foregoing I have hereunto subscribed my name this 16 day of April, 1918.

AUGUST J. HARTFIELD.

Witness:

VIRGINIA I. BERRINGER.
